UNITED STATES PATENT OFFICE.

FRANK E. CAMPBELL, OF NEW YORK, N. Y.

AMBULANCE-AUTOMOBILE.

1,099,020.

Specification of Letters Patent.

Patented June 2, 1914

Application filed April 3, 1912, Serial No. 688,167. Renewed January 31, 1914. Serial No. 815,831.

To all whom it may concern:

Be it known that I, FRANK E. CAMPBELL, a citizen of the United States, and a resident of the city of New York, borough of Manhattan, in the county and State of New York, have invented a new and Improved Ambulance-Automobile, of which the following is a full, clear, and exact description.

Among the principal objects for which the present invention is designed are: to provide means for, at will, converting an automobile of usual construction to adapt the same for employment as an ambulance; to provide an ambulance of the character mentioned, which may be arranged for the introduction of the stretcher or carrier for the patient in the ambulance, without forcing the persons carrying the stretcher to step into the street; to provide means within the automobile whereby the stretcher and patient may be introduced sidewise into an automobile, and thence moved across the body to provide a passageway for passengers entering from the same side of the automobile; to provide an extension to the body of the automobile, adapted to hold a portion of the person of the patient; and to provide a shelf or rest for the stretcher, upon which the stretcher may be deposited, and over which the stretcher may be moved in depositing the same within the body of the automobile.

Reference is to be had to the accompanying drawings forming a part of this specification, in which similar characters of reference indicate corresponding parts in all the views, and in which—

Figure 1 is a side elevation of the approved form of automobile ambulance, constructed and arranged in accordance with the present invention; Fig. 2 is a horizontal plan section taken on the line 2—2 in Fig. 1.

Automobiles of the character indicated are employed for carrying the sick in a manner less public than that at present involved, wherein the ordinary ambulance for the sick is attended with more or less confusion, bustle and undesirable attention. The public feature of the conveyance is objectionable to many persons, and it is to overcome these objections that I have provided an automobile vehicle equal in its equipment to the so called touring car, which is adapted for the introduction and withdrawal of a litter. Another employment for which the automobile is designed is the carriage of the dead, being substituted for the hearse of

usual construction. With these purposes in view, I construct a body for an automobile of sufficient length to receive the litter or stretcher on which a patient is prone, or I alter the body construction of the usual automobile to provide the necessary dimensions in the said body of the usual automobile. The preferred form is that shown in Figs. 1 and 2, where it will be seen that the body 10 is elongated, to comfortably contain a full-length stretcher or bed 11. The body, as seen in the drawings, is provided with an elongated side panel 12, which is hinged at the lower edge at 14, 14. The hinges 14, 14 are disposed at the lower edge of the panel 12, which, when closed in the upright position, is held firmly by latches 15, as seen best in Fig. 1 of drawings. In the closed position of the panel 12, the body of the automobile is in most respects the same as that of the ordinary coach.

To accommodate the passage of the bed 11 when the panel 12 is let down, as shown in Fig. 2 of drawings, I hang the door 16 on hinges 17 disposed at the forward edge of the door and door opening. It will be seen by reference to Fig. 2 of drawings, that when the door 16 is opened, a passageway is provided, combining as it does the full opening of the door 16 and the opening of the panel 12. For all ordinary purposes, the combined length of the door and panel above mentioned is sufficient. Provision is made, however, for an emergency, by constructing the body with a removable rear panel 18. When the panel 18 is removed, it will be seen that the stretcher or bed 11 may be rested on the panel 12 and moved lengthwise and obliquely into the body of the panel, the one end of the stretcher or bed being permitted to extend through the space normally occupied by the panel 18. When the opposite end of the stretcher has sufficient clearance to pass the door 16 and the frame 100 therefor, the stretcher is swung to a position parallel with the side of the body, and is then adjusted so that the panels 12 and 18 may be closed.

Should it prove desirable that the bed 11 shall be shifted sidewise and laid upon the rack or cushions on the rack at the opposite side of the body, this may be done, and the cushions which have rested previously on the brackets 19 may be replaced, for the convenience of the passengers of the automobile.

The brackets 19 are of usual construction. It is desired, however, that the level of the horizontal arms of the brackets 19 should be disposed approximately flush with the 5 upper side of the panel 12, when horizontally extended. When this is arranged as indicated, it makes a convenient floor for the handling of the stretcher or bed 11.

When employing a vehicle of the construction indicated, the stretcher or bed 11 is brought from the house and is deposited upon the panel 12, which is supported in horizontal position by a mud-guard 20 prior to moving the stretcher or bed into the body 10 of the vehicle. The stretcher or bed is then shifted laterally over the panel 12 upon the brackets 19. When the bed has been shifted to proper position in the body, the panel 12 is closed. It will be noted that in this 15 operation, one of the attendants may pass through the opening of the door 16, to ease or regulate the movement of the stretcher. When thus employing the vehicle, the cushion 20 is removed from the brackets 19. If the stretcher is not used, cushions the duplicate 25 of those indicated in the drawings may replace the stretcher on the brackets 19 to form sides.

Having thus described my invention, I 30 claim as new and desire to secure by Letters Patent:—

1. An automobile having a body provided with an L-shaped entrance opening, one extension of said opening being substantially 35 parallel with the floor of said body; and a plurality of doors for said opening, one of said doors being vertically disposed to cover the vertical extension of said opening, said door being swung at the edge of said vertical extension remote from said horizontal extension.

2. An automobile having a body provided with an L-shaped entrance opening, one extension of said opening being vertical and the other horizontal; a closure door for the vertical extension of said opening, hinged at the edge thereof remote from said horizontal extension; and a closure door for the horizontal extension to register, when closed, with the first-mentioned door. 45

3. An automobile having a body provided with an L-shaped entrance opening, one extension of said opening being vertical and the other horizontal; a closure door for the vertical extension of said opening, hinged at the edge thereof remote from said horizontal extension; and a closure door for the horizontal extension, said door being pivotally connected at the lower edge thereof 50 to fall outwardly to form a rest for a litter when introduced into said cab body through the horizontal extension of said opening. 55

4. An automobile having a cab body provided in the one side thereof with an L-shaped opening, one extension of said opening being substantially horizontal and adapted to have passed therethrough a litter; and a plurality of closure doors for said horizontal extension, one of said doors being pivotally connected to the edge forming the vertical extension of said opening, 60 the other of said doors being pivotally connected to the horizontal edge of the portion of the horizontal extension exclusive of said vertical extension. 65

In testimony whereof I have signed my name to this specification in the presence of two subscribing witnesses.

FRANK E. CAMPBELL.
